DESIGN FOR A CASING FOR A TOASTER OR SIMILAR ARTICLE

Andrew S. Knapp, St. Louis, Mo., assignor to
Knapp-Monarch Company, St. Louis, Mo., a
corporation of Missouri

Application January 6, 1936, Serial No. 60,454

Term of patent 7 years

To all whom it may concern:

Be it known that I, Andrew S. Knapp, a citizen of the United States and a resident of the city of St. Louis and State of Missouri, have invented a certain new, original, and ornamental Design for a Casing for a Toaster or Similar Article, of which the following is a specification, reference being had to the accompanying drawing, forming part hereof.

Figure 1 is a perspective view of a casing for a toaster illustrating my design.

Figure 2 is a front elevation of same.
Figure 3 is an end elevation of same; and
Figures 4 and 5 are sectional views on the
lines 4—4 and 5—5 of Figures 2 and 3 respec-
tively.

The dominant features of the design are shown in full lines.

I claim:

The ornamental design for a casing for a toaster or similar article as shown and described.

ANDREW S. KNAPP.
